SHOE BUFFER

Ernest L. Hollenbeck, Los Angeles, Calif.

Application April 24, 1937, Serial No. 138,770

3 Claims. (Cl. 15—231)

My invention relates to and has for a purpose the provision of a shoe buffer which is characterized by its structural simplicity, low cost of manufacture, easy mode of assembly of its parts to facilitate manufacture and equally easy of disassembly to allow substitution of a new strip of buffering material when required.

I will describe only one form of shoe buffer embodying my invention, and will then point out the novel features thereof in claims.

In the accompanying drawing:

Fig. 1 is a view showing in top plan one form of shoe buffer embodying my invention.

Fig. 2 is a longitudinal sectional view taken on the line 2—2 of Fig. 1.

Fig. 3 is a detail plan view of the frame comprised in the buffer.

Fig. 4 is a detail plan view of the spring member embodied in the buffer.

Referring specifically to the drawing, my shoe buffer essentially consists of a spring member S, a frame F and strip B of suitable buffering material such as the sheep skin shown.

The member S is made from a length of spring metal or other spring material to provide a flat elongated body 15 having end portions which are curved and extended to the same side of the body to form a pair of opposed hooks 16, 16.

The frame F is formed of a single length of inflexible wire which is bent in the general form of a rectangle (Fig. 3) to provide end portions 17, 17 and side portions 18, 18. The side portions are bowed outwardly to one side of the frame, while the end portions are bent inwardly toward each other for a major portion of their length to form projections, 19, 19 disposed in the plane of the indented portions.

The strip of sheep skin B is of a width to exceed that of the frame F, while its length is such that it can be extended lengthwise around the front side of the spring member S, then around and into the hooks 16, 16, and finally across the back of the spring so as to completely cover it and thus provide a soft surface for the fingers of the user when gripping the frame F, in addition to giving a desirable finish to the back of the buffer.

To assemble the aforescribed elements in the formation of the buffer, the spring S is placed on the smooth or skin side of the buffering strip so as to extend longitudinally thereof to be disposed medially of its ends. The ends of the buffering strip are now folded over and pressed into the hooks, to position the free ends of the strip flat against the back of the spring.

The frame is now applied by first inserting the

indented part of one end portion into one of the hooks 16, and then inserting the other indented part of the other end portion into the other hook. As the frame is designed, its length exceeds the distance between the hooks, hence, in order to cause the last end portion of the frame to pass into the respective hook, it is necessary to flex the spring body 15 inwardly at its center sufficiently to move the hook to an angle in which its free end together with the buffering material clears the frame.

With the frame F applied as described, the spring S is held under tension to urge the hooks toward the frame ends, and thus the hooks are caused to coact with the frame ends to clamp the buffering strip between the two and with such security as to maintain the strip against slipping lengthwise on the spring.

Accidental displacement of the frame edgewise from the hooks is prevented by the projections 19 abutting the opposite edges of the hooks 16 through the buffering strip. Thus, once the frame is snapped in place, it is immovable on the buffering strip and spring, and can be removed only by exerting sufficient pull on either end of the strip to remove it from between one frame end and the respective hook, when the frame becomes detached from both of the hooks.

Manifestly, the bowed side portions of the frame provide a handle which is adapted to be gripped in manipulation of the buffer in the polishing of shoes.

Although I have herein shown only one form of shoe buffer embodying my invention, it is to be understood that various changes and modifications may be made herein without departing from the spirit of my invention and the spirit and scope of the appended claims.

I claim:

1. A shoe buffer, comprising; a flat spring member having terminal hooks; a strip of flexible material covering the outer side of said member and extended into said hooks; and a rigid member having indented end portions extending into the hooks and against the material, so that the hooks and the rigid member coact to secure the material within the hooks and to confine the members against lateral displacement.

2. A shoe buffer, comprising; a flat spring member having terminal hooks; a strip of flexible material covering one side of said member and extended into said hooks; and a frame having spaced projections on the ends thereof, between which the hooks of said member are received, said frame coacting with said hooks to secure the

strip within the hooks and said projections confining the hooks against lateral displacement from the frame.

3. A shoe buffer, comprising; a flat and narrow spring member having terminal hooks; a strip of buffing material extended around one

side of said member and into said hooks; and a frame having ends wider than the member extended into said hooks for securing said strip therein and for holding said strip in extended position at the ends of the member.
